UNITED STATES PATENT OFFICE.

JASON C. STEARNS, OF WORCESTER, MASSACHUSETTS.

COMBINED TONNEAU AND TROUBLE LAMP.

1,311,295.

Specification of Letters Patent. Patented July 29, 1919.

Application filed March 31, 1919. Serial No. 286,397.

To all whom it may concern:

Be it known that I, JASON C. STEARNS, a citizen of the United States, residing at Worcester, in the county of Worcester and State of Massachusetts, have invented a new and useful Combined Tonneau and Trouble Lamp, of which the following is a specification.

This invention relates to a tonneau lamp for automobiles so constructed as to be capable of use in an efficient and convenient manner as a trouble lamp.

The object of this invention is to provide simple and inexpensive detachable devices by which the lamp can be so mounted as to be able to accomplish both of these results and it involves special provisions for that purpose as will appear.

Reference is to be had to the accompanying drawings in which—

Figure 1 is a perspective view of a tonneau lamp shown in position on the wall of a tonneau and constructed in accordance with the present invention;

Fig. 2 is an elevation of the lamp supporting and attaching ring showing the reverse side, with the lamp in position therein;

Fig. 3 is a sectional view on the line 3—3 of Fig. 2;

Fig. 4 is a view similar to Fig. 2 showing a modified construction, and

Fig. 5 is a sectional view on the line 5—5 of Fig. 4.

Referring first to the first three figures it will be seen that when the lamp 10 is in place on the wall 11 of the tonneau, whether it is the front wall or otherwise, it has the appearance of the usual tonneau lamp, being supported by a surrounding ring 12 connected with the wall of the tonneau by screws 13 or the like. However, beyond the wall 11 there is a space in which a coil or at least a length of electric light cable 14 connected with the lamp can be stored. This cable, of course, is connected up with any usual source of power to supply the lamp.

Although the ring 12 is of the usual appearance outside it is formed with a circular projection 15 concentric with the lamp and furnishing a flat wall against which the flange of the lamp rests, and a recess under it for a spring 16. This spring in the pres-

ent case consists of a single piece of wire almost entirely surrounding the lamp inside the ring 12 but not of circular shape. It is shown in the present case as supported from the ring by three clips 17 through which the wire passes and having its ends 18 separated from each other to allow for expansion and contraction. This wire spring is also flattened in three places 19 between the clips 17 so that these flattened portions will engage the circumferential groove 20 in the rear body 21 of the lamp.

The parts being assembled as shown in Figs. 1, 2 and 3, the lamp serves ordinarily as the usual tonneau lamp, but when it is desired to use it for a trouble lamp it is pulled out by the application of pressure to release it from the spring 16. This can be accomplished by taking hold of the flange of the lamp and pulling it directly out, or if that does not release it, tipping it first in one direction and then in the other. The leverage thus secured releases it from the spring. Then the lamp can be handled in a very convenient way and used as long as may be desired within the car or near it. The coil of wire 14, of course, permits of this action. When it is desired to return it the wire is first tucked in beyond the wall 11 and then the lamp forced into place by merely pushing it backward in the ring 12.

In the form shown in Figs. 4 and 5 the same operation and the same principles are retained, but the lamp itself instead of the groove 20 is provided with a circumferential bead or projection 25 and the inside of the ring 26 has three spring clips 27, each one having a tongue 28 provided with a recess 29 for receiving the bead 25. For convenience these clips may be secured to the ring by eyelets 30 passing through the holes which receive the screws 13 shown in Fig. 1. The results are substantially the same as in the other figures, and its uses and operation need not be described in detail.

Although I have illustrated and described only two forms of the invention I am aware of the fact that many modifications can be made therein without departing from the scope of the invention as expressed in the claim. Therefore I do not wish to be limited to all the details of construction herein

shown and described but what I do claim is:—

The combination with a supporting ring mounted on the vertical wall of an automobile and substantially flush with the surface thereof and having a central passage therethrough, of a tonneau lamp adapted to be supported within said ring and passage and

beyond said wall, the front surface of the lamp lying substantially in the plane of said ring, and yielding means within the ring for detachably holding the lamp therein but allowing it to be turned.

In testimony whereof I have hereunto affixed my signature.

JASON C. STEARNS.
